UNITED STATES PATENT OFFICE.

BYRON B. LEE AND JESSE DOWNS, OF NASHVILLE, MICHIGAN.

GRAIN WEIGHING AND REGISTERING APPARATUS.

SPECIFICATION forming part of Letters Patent No. 367,985, dated August 9, 1887.

Application filed February 15, 1887. Serial No. 227,751. (No model.)

To all whom it may concern:

Be it known that we, BYRON B. LEE and JESSE DOWNS, citizens of the United States, residing in the village of Nashville, in the county of Barry and State of Michigan, have invented a new and useful Machine for Weighing and Registering, of which the following is a specification.

Our invention relates to improvements in machines designed to automatically weigh and discharge grain or other materials and register the amount of the same.

The objects of our invention are to provide means whereby a continuous stream of grain is allowed to run into buckets alternately, the flow being shifted automatically upon the accumulation of a certain amount, to which the machine may be adjusted; also, to automatically discharge the contents of said buckets and make a register of the same. These objects are accomplished by the mechanism illustrated in the accompanying drawings, in which—

Figure 1 is a side elevation of a machine embodying our invention; Fig. 2, a plan, with part of the frame and scale-beam broken away; Fig. 3, an elevation of the registering mechanism; Fig. 4, a central vertical section of the shifting mechanism on a plane parallel to the bar E; Fig. 5, an elevation of the same at right angles to the plane of Fig. 4, broken away to show the upper pivot on section; Fig. 6, a plan of mechanism for operating shifting mechanism.

Like letters and figures refer to like parts in all the figures.

Suspended within a suitable frame-work by means of hangers N are two scale-beams, F F, which pass through loops R to limit their movement, from which are suspended two buckets, A A, connected by rods I to the frame to keep them in position, which receive the stuff to be weighed, which is to be conducted to said buckets by means of the stationary pipe D, the movable pipe C, and the divided pipe B, which latter is divided into two branches, u u, at its lower end, which open into the respective buckets A A.

Pivoted between said hangers N are bell-crank O O, one arm of which is parallel, and connected to the scale-beams F F by means of

link T, pivoted to each. The other arm of said bell-crank rises vertically from the pivot, and is provided near the upper end with adjustable weights P, supported upon a bar having screw-threads engaging with similar threads in said weights. The upper ends of said vertical arms are extended horizontally to a point near the upper end of the movable pipe C, where they terminate in a vertical pin, which engages with a rod, r, extending through said pipe and projecting from its opposite sides. From the middle of said rod r rises vertically a pivot pin, v, which engages with a hole in the under side of a bar, s, extending across the axis of and secured to the stationary pipe D. Thus the upper end of the pipe C incloses and revolves about the lower end of the pipe D.

Directly below the pivot s is the lower pivot, S, which is attached to the pipe C, and placed a suitable distance outside the same to cause its lower end to swing from side to side of the pipe B, within which it is suspended by the aforesaid pivot. The bottom H is attached at one side by the hinge M, and when the bucket as empty is closed by the weight J, attached by the rod t and adjustable thereon, and held closed by a pivoted hook, L, having an arm extending upward between the tracks G, which are pivoted at U and attached at their outer ends to the respective outer ends of the scale-beams F by means of rods Q, of such length that when said beams are down the tracks will incline outward, and when said beam rises the said tracks will be inclined inward or toward the buckets A.

K are balls which roll to and fro upon said tracks on their inward movement, striking the arms w and releasing the bottoms H, and on their outward movement striking the levers k, attached to a rock-shaft, g, which actuates a ratchet-wheel, b, by means of a pawl pivoted to an arm, i, upon said shaft, and having a weighted arm, j, to keep it in contact with said wheel. Said lever k is inclosed by a loop, l, to limit its backward movement, and pushed back by a spring, m, inclosing said loop. Resting upon the wheel b is a spring, g, to prevent its moving too freely. n is a screw to regulate the pressure of said spring.

f is a tape having a scale thereon spaced in conformity to the distance moved by the roll b'

at each movement of the ratchet-wheel, to which said roll is attached by a shaft passing through both. Said tape is delivered from a roll, *c*, passes partly around the roll *b'*, with which it is brought in close contact by the roll *c*, journaled in slotted openings in the frame *a*. Said tape is thence conveyed to a roll, *d*, upon which it is wound by the action of the weight *p*, attached to a drum-cord, *z*, which is wound 10 about a drum, *o*, upon the shaft of the said roll *d*.

Instead of connecting the bell-crank directly to the projecting ends of the rod *r*, I prefer to adopt the device shown in Fig. 6, in 15 which the bell-crank *O* engage with the levers *5*, pivoted at *6* to a frame, *I*, which also supports a segment-gear, *3*, also pivoted to said frame *I* at *2*, said gear engaging with a pinion upon the upper end of pipe *C*, and actuated by 20 the levers *5*, which engage with pins *7* in said segment-gear. We can by this means get a quicker movement of the pipe *C* when the beam *F* rises than by the other device.

The operation of our invention is as follows: 25 The grain or other stuff to be weighed and registered is allowed to flow in a continuous stream through the pipes *D*, *C*, and *B*. It will pass through whichever division *u* that pipe *C* may be over and into the respective bucket *A*. 30 When a sufficient amount has accumulated, which is determined by the adjustment of the scale, the scale-beam will rise, carrying with it the bell-crank *O* and track *G*. The bell-crank striking against the rod *r* turns the pipe *C* 35 upon the pivots *s* *S* and shifts the stream into the other bucket, and so on alternately. In case of the device in Fig. 6, the bell-crank engages with the lever *5*, and through it imparts motion to the gear *3*, which in turn rotates the 40 pipe *C*, by means of the pinion *4*, simultaneously with the described cut-off movement. The outer end of the track *G* is elevated, the ball *K* rolls inward, passing under the lever *k* without touching it, and strikes the arm *w*, releasing the bottom *H*, which is opened by the weight 45 of the contents of the bucket, which contents are discharged in a body, and the bottom quickly restored to its former position by the weight *J*. Relieved of its load the beam *F* 50 now falls, which retracts the bell-crank to its former position and again inclines the track *G* outward, when the ball *K* returns. The track *G* now being higher at its inner end, each ball strikes the lever *k* and moves the wheel *b* one 55 notch, which moves the tape *f* one space of its scale by means of the roll *b'*. All the parts are now ready to repeat the operation described as soon as the opposite side operates to shift the stream by operations already 60 described. Each side operating alternately, as described, disposes of a constant stream of stuff

without stoppage, weighs it accurately, and registers the total amount from a given time. At the end of the operation, or from time to time, a crank can be applied to the end of the 65 shaft through the roll *c* and the register wound up.

What we claim and wish to secure is as follows:

1. In combination with a scale-beam having 70 a bucket attached having a bottom adapted to open and discharge the contents of said bucket when released, a pivoted track, and a ball adapted to roll upon said track and release said bottom, substantially as described. 75

2. In combination with a scale-beam having attached a bucket with a bottom adapted to open and discharge the contents of said bucket, and a track carrying a ball adapted to traverse said track and release said bottom, and a 80 register adapted to engage with said ball and indicate its movements, substantially as described.

3. In a weighing-machine, in combination with the scale-beam *F* *F* and movable pipe *C*, 85 the pinion *4*, segment-gear *3*, pivoted lever *5*, and bell-crank *O*, substantially as described.

4. In a weighing-machine, a shifting-pipe having a pivot within its axis at its upper end and a pivot outside of its axis at its lower end, 90 in combination with a stationary pipe above and a divided pipe below said shifting pipe, substantially as described.

5. In a weighing-machine, a registering device consisting of a tape, *f*, rolls *b' c d e*, a 95 ratchet-wheel, *b*, pawl *h*, rock-shaft *g*, springs *g* and *m*, lever *k*, and loop *l*, substantially as described.

6. In a weighing-machine, a bucket suspended from a scale-beam, having a hinged 100 bottom, *H*, in combination with the weight *J* and latch *L*, pivoted track *G*, ball *K*, scale-beam *F*, and rod *Q*, substantially as described.

7. In a weighing-machine, the combination of buckets suspended from scale-beams, having 105 bottoms adapted to open when released and discharge the contents and again automatically close, a stationary pipe above said buckets, a movable pipe adapted to alternately connectsaid stationary pipe with said buckets, 110 pivoted tracks adapted to tilt in unison with said scale-beams, balls adapted to traverse said track and release the bottom of said buckets, and a mechanism adapted to register the discharges of the contents of said buckets, 115 substantially as described.
